UNITED STATES PATENT OFFICE.

JACOB N. BARR, OF MILWAUKEE, WISCONSIN.

CAR-DOOR.

SPECIFICATION forming part of Letters Patent No. 631,496, dated August 22, 1899.

Application filed July 15, 1898. Serial No. 686,056. (No model.)

To all whom it may concern:

Be it known that I, JACOB N. BARR, a citizen of the United States, residing at Milwaukee, in the county of Milwaukee and State of Wisconsin, have invented a certain new and useful Improvement in Car-Doors, (Case 2,) of which the following is a full, clear, concise, and exact description.

My invention relates to doors, and particularly to doors for cars; and it consists in certain improvements whereby the door-opening is more completely closed against storm, sparks, and cinders.

Another object of my invention is to provide a door which fully frees itself from the side of the structure which it incloses by an outward movement of the door bodily before the door-opening is fully uncovered.

Another object of my invention is to provide a door which is removed far enough from the sides of the structure which it incloses to permit it to slide along the side of the inclosure without coming in contact with the side when the door is warped or the side of the inclosed structure is bulged outward.

Still another object of my invention is to provide a door acting as above without complication of joints, levers, and retaining parts, which are liable to get out of order and which are expensive to maintain in proper working condition.

My invention I will describe as applied to a freight-car; but it will be obvious that its application to other structures can readily be made, and my invention is not limited in its application to cars.

In the doors of freight-cars as heretofore constructed it has been difficult to provide means for sliding the doors when the freight within the car has caused the sides of the car to bulge outward or when the door itself has become warped by use or by exposure to the weather. In order to allow freedom sufficient to permit the movement of the door freely, it has heretofore frequently been necessary to leave a margin between the door and the sides of the car which would permit access of rain and cinders. The difficulties above referred to and others, which it is the object of my invention to obviate, have increased and become more serious with the increasing size of cars which it is now customary for railroad

companies to use, and many attempts have been made to overcome these difficulties.

I will describe my invention by reference to the accompanying drawings, in which—

Figure 1 is a front view of the car-door in a closed position. Fig. 2 is a cross-sectional view of the car-door on line 2 2, Fig. 1, with the door in its closed position. Fig. 3 is a cross-sectional view of the car-door on line 3 3, Fig. 1, with the door in its open position. Fig. 4 is a side view of the shoe which supports the car-door, partly in section, and of the lock in place therein. Fig. 5 is a front view of the same part shown in Fig. 4. Figs. 6 and 7 are respectively side and rear views of the lock. Fig. 8 is a top view of the shoe and lock, partly in section. Figs. 9 and 10 are views of modifications of the shoe and lock of my invention.

Similar letters of reference refer to similar parts in all the different views.

In Fig. 1 the car-door *a* is shown in its closed position, with cleats *a' a'* upon the side of the car at each end of the door and forming a recess in which the door is located. These cleats protect the space, whatever it may be, between the sides of the car-door and the car, so that sparks or rain cannot gain access to the interior of the car. The door is supported upon the shoes *b b*, which rest upon the rail *c* and are adapted to slide thereon parallel with the side of the car. The rail is supported upon the brackets *c' c'* and only a part of its length is shown, it being understood that it would be long enough to permit the door to be carried upon it, so as to fully uncover the opening in the side of the car. A sheet-iron strip *d* extends along the top of the door and is attached to the car so as to serve as a guide and prevent the door from falling outward, the portion *d* extending below the top of the door in its upper or lower position and acting as a guard.

In Fig. 2, which shows the door *a* in its closed and locked position, there is shown a groove *e*, in which the top of the door rests in its closed position. I preferably make a chamfer *e'* in the timber forming the groove, so as readily to permit the tilting of the door outward in a manner which I will later describe.

In the closed position of the door the shoes

b b hold the door close against the side of the car; but in the initial movement of the door to open the same the shoes, which are attached to the bottom of the door, are permitted to move downward and outward, and the top of the door also tilts outward, so that before the door is moved upon the rail along the side of the car it reaches the position shown in Fig. 3, in which it is bodily moved outward from its seat to a position which will enable it to slide past the cleats and also to enable it to pass freely along the car side even when the sides of the car may be bulged outward by the enclosed freight. I have found in practice that a movement of two inches outward of the door is sufficient to secure satisfactory results with the construction herein described, although a less initial movement may be satisfactory under certain conditions and a greater movement may be required under certain other conditions.

In order to permit the entrance of the top of the door into the groove *e*, I may cut away a portion of the timber *e²*, which forms the groove above the central portion of the opening which the door is to cover. Then if the door becomes bulged at its center it will still enter the grooves and be held firmly in place in its closed position.

30 Figs. 4, 5, 6, 7, and 8 represent one form of shoe and lock which I have adopted, in which the latter is separate from the shoe and moves therein, and this construction I will now proceed to describe.

35 The shoe *b* is provided with a latch or catch *f*, which in the position shown in Fig. 4 prevents any outward movement of the door from the closed position by the engagement of the projection *f'*, which drops below the upper edge of the rail *c*. This catch *f* can be raised by pressing upward against it at the point *f²*, which raises the projection *f'* above the upper edge of the rail. When the catch *f* is thus raised, the lower part of the door *a* is free to move outward into the position shown in Fig. 3, while the top of the door drops down out of the groove *e* and rests against the strip *d*. I have shown in Fig. 4 in dotted lines the position of the catch *f* when it is raised to permit the downward and outward motion of the shoe *b*. It will be seen that the shoe *b* has a horizontal portion *b'*, an incline *b²*, and another horizontal portion *b³* and that the catch *f* is provided with similar horizontal and inclined faces. The horizontal portion of the catch, which rests upon the top of the rail when the car-door is closed, however, is within a recess formed by the projection *f'*, and before the shoe can be released the catch 55 must be raised to allow the projection *f'* to pass over the top of the rail, when the car-door slides down the incline *b²* of the shoe and finally rests upon the horizontal portion *b³* of the shoe, being prevented from passing over 60 the rail by the downwardly-projecting part of the shoe *b⁴*. The catch *f* is provided with

a hole *f³*, which registers with a hole *c²* in the rail when the door is closed to permit the admission of a wire for sealing the door. In Figs. 6 and 7 the catch is shown detached from the shoe, and Fig. 8 is a section on line *x x* of Fig. 5.

Figs. 9 and 10 represent modifications of the shoe and catch of my invention, in which the catch is made a portion of the shoe. The catch *f* in this case is eccentrically and rotatably mounted upon the pivot *p*. In this construction I preferably provide a projection *b⁵* upon the shoe itself, which will engage the rail when the door is in its closed position, and by means of the eccentric the whole door is raised slightly by the rotation of the catch *f*, so as to permit the outward and downward movement of the shoe upon its inclined surface *b²*. I provide also a lip *f⁴*, which engages with the rail *c*. The lever *f⁵*, by means of which the rotary movement is given to the cam-formed latch *f*, is provided with an opening *f³*, which registers with the opening *c³* in the rail to permit the sealing of the door in its closed position. I preferably so construct the door that the top will tilt outward by gravitation when the downward and outward movement is given to the bottom of the door.

The operation of the door of my invention 95 will be readily understood from the foregoing description. To open the door, the latches *f f* are raised, being thereby disengaged from the rail, and a pull upon the bottom of the door in an outward direction brings the door 100 downward and outward on the inclined face of the shoe until the portion *b³* of the shoe rests upon the rail. At the same time the top of the door moves downward and outward and the door assumes the position shown in 105 Fig. 3, when it is free to move easily along the rail and behind the strip *d* without striking the cleats or binding against the side of the car. To close the door, it is pushed along until it is in front of the opening which 110 it is to cover. A pressure is then exerted against the door some distance above the lower edge. This causes the top of the door to tip inward until it registers with the groove *e*. A further pressure at the lower edge of 115 the door forces it inward and upward upon the inclined surfaces of the shoe, bearing upon the rail until the door reaches the position shown in Fig. 2. The catch *f* then drops down and holds the door firmly in place. With the modifications shown in Figs. 9 and 120 10 the arm *f⁵* is rotated to the position shown in both figures, when the shoe is in position to permit the outward and downward movement of the bottom of the car-door in the 125 same way already described. When the door is to be closed, an inward pressure is exerted, first at the top of the door to tilt the door into a position so that the top will engage with the groove *e*. A further pressure on the bottom of the door pushes it inward and at the same time raises it, when the arm *f⁵* is rocked 130

into position so that the lip f^4 engages with the rail c and the hole f^2 in the arm registers with the hole c^2 in the rail.

The recess or groove that I have provided upon the front face of the door-frame and at its upper portion is adapted by its shape to receive the top of the door and to secure the top portion of the door close to the door-frame to close the doorway or in a position removed from the door-frame when the lower portion of the door has been moved outwardly and downwardly. To accomplish this result, the lower and outward edge of the recess or groove is extended horizontally outward a sufficient distance to permit the required outward movement of the door when in its lowered position and then vertically downward to stop the edge of the door in its outward movement. The groove in this form is then extended longitudinally to provide means for sliding the door away from the door-opening. It will be observed that when the door is in its outermost position it is not necessary to employ nor do I employ in the preferred construction any inner guiding-surface to direct the top of the door in its travel.

The door and its appurtenances are preferably so arranged that the track upon which the door is supported will lie in a plane between the center of gravity of the door and the side of the car when the lower portion of the door is moved outwardly and downwardly and the upper portion of the door is tilted toward the car, whereby the upper portion of the door is, through the agency of gravity, moved outwardly and into engagement with the rail or strip d , which preferably acts as the sole guide for the upper portion of the door. The inclines b^2 upon the shoes form a downwardly and outwardly engaging surface at the lower edge of the door, the horizontal surfaces b' b^3 lying in different planes, the horizontal surface b^3 nearer the door-frame being above the horizontal surface b' , whereby the door may be supported close to the door-frame when it is elevated and away from the door-frame when the door is lowered. I do not wish to be limited to the employment of the rail for securing the door in its elevated position.

Instead of having the entire groove e disposed upon the exterior of the car the inner and uppermost part of the groove may be extended within the doorway and located between the side margins thereof, as shown, whereby when the door is elevated and moved into its closed position it is disposed between the side margins of the doorway and may be made flush with the side of the car. With this construction the lower and outermost part of the groove e is extended longitudinally beyond the doorway to act as a guide to the door in its travel. I do not wish, however, to be limited to this feature, as I consider it to be broadly new with me to provide a groove at the upper portion of the doorway and mak-

ing the inner portion of the groove extend above the outer portion thereof, so constructing the groove that it is capable of engaging the door to secure it in its elevated and closed position or in its lowered and unclosed position, and in extending the lower outer part of said groove longitudinally beyond the doorway to retain the top portion of the door in its lower and outermost position in its horizontal travel. By so constructing the groove that it may coöperate with the door in the manner pointed out no additional mechanism need be provided at the top of the door for controlling the position of the upper portion thereof and in compelling the movement of the door toward the doorway upon the elevation of the door.

I am aware that car-doors have been so mounted as to have an inner and upward movement and an outer and downward movement, to effect and control which, however, auxiliary mechanical devices have to be employed at the upper portion of the door, which devices I am enabled to dispense with by constructing the groove as shown and described. Moreover, by providing fixed bearing devices affording two points of support for the door at different levels and at different distances from the car, as described, which devices are capable of permitting the door to have free movement transverse to the car, all of the desired movements of the door may be accomplished without the aid of any lever or screw mechanism whatsoever.

I am aware that sliding car-doors have been provided at their bottom portions with surfaces inclining downward toward the car; but such means only serve to aid in keeping the door closed and do not aid in keeping the door open. My supporting devices by being placed as shown and described aid in keeping the door open or shut, as the case may be.

I do not wish it to be understood that my invention is limited to the precise form and detail of construction shown herein. It is susceptible of many modifications which are within the spirit of the broad invention described. I believe I am the first one to construct a door which is adapted to be held firmly seated in its closed position, but which is initially moved bodily outward away from its seat before the opening which it is intended to cover is disclosed by sliding along a rail parallel with the side of the inclosed structure. It is this invention which I desire to cover, not only in the specific embodiment shown and described herein, but in all its equivalent modifications, in the following claims.

I claim—

1. The combination with a shoe for a door, of a rail upon which said shoe is adapted to rest and to slide, a latch adapted to hold said shoe in engagement with said rail when the door is closed and to permit an outward movement of said door, the rail being provided

with a hole for providing a locking engagement between the latch and the rail, substantially as described.

2. The combination with a door *a*, of cleats *a'* *a'*, of a groove *e* adapted to receive the top of said door, the shoes *b* attached to the bottom of said door, the rail *c* upon which said shoes are adapted to rest and to slide, the latch *f* adapted to hold the shoes in engagement with said rail and to permit a downward-and-outward movement thereof preparatory to sliding the door away from said opening.

3. The combination with a door-frame, of a vertically-movable sliding door, a groove being provided at the upper portion of the door, said groove being higher nearer the doorway and lower away from the doorway, the outer wall or portion *d* of the groove extending below the top of the door in its lowered position, said groove being thus adapted to engage and secure the top of the door close to the doorway when the door is elevated, and to permit it to move away from the doorway when the door is lowered, means for supporting the door in its elevated or lowered position, and means for guiding the door in its horizontal travel when lowered, substantially as described.

4. The combination with a door-frame, of a vertically-movable sliding door, a groove being provided at the upper portion of the doorway and being higher nearer the doorway and lower away from the doorway, the outer wall or portion *d* of the said groove extending below the top of the door in its lower position, said groove being thus adapted to engage and secure the top of the door close to the doorway when the door is elevated and away from the doorway when the door is lowered, and serving to compel the movement of the door, when elevated, toward the doorway, all without the aid of auxiliary devices, the outer and lower portion of said groove being extended longitudinally of the doorway beyond the same to retain the top portion of the door in its lower outermost position in its horizontal travel, means for supporting the door in its elevated or lower position, and means for guiding the door in its horizontal travel when lowered, substantially as described.

5. The combination with a door-frame, of a vertically-movable sliding door, a groove being provided at the upper portion of the doorway and being higher nearer the doorway and lower away from the doorway, the outer wall or portion *d* of the said groove extending below the top of the door in its lower position, the inner and upper portion of said groove being disposed between the side margins of the doorway, whereby the door may be closed flush, said groove being thus adapted to engage and secure the top of the door close to the doorway when the door is elevated and away from the doorway when the door is lowered, and serving to compel the movement of the door, when elevated, toward the doorway, all without the aid of auxiliary devices, means

for supporting the door in its elevated or lower position, and means for guiding the door in its horizontal travel, when lowered, substantially as described.

6. The combination with a door-frame, of a vertically-movable sliding door, a groove being provided at the upper portion of the doorway and being higher nearer the doorway and lower away from the doorway, the outer wall or portion *d* of the said groove extending below the top of the door in its lower position, the inner and upper portion of said groove being disposed between the side margins of the doorway, whereby the door may be closed flush, said groove being thus adapted to engage and secure the top of the door close to the doorway when the door is elevated and away from the doorway when the door is lowered, and serving to compel the movement of the door, when elevated, toward the doorway, all without the aid of auxiliary devices, the outer and lower portion of said groove being extended longitudinally of the doorway beyond the same to retain the top portion of the door in its lower outermost position in its horizontal travel, means for supporting the door in its elevated or lower position, and means for guiding the door in its horizontal travel, when lowered, substantially as described.

7. The combination with a door-frame, of a vertically-movable sliding door, a groove being provided at the upper portion of the doorway and being higher nearer the doorway and lower away from the doorway, the outer wall or portion *d* of the said groove extending below the top of the door in its lower position, said groove being thus adapted to engage and secure the top of the door close to the doorway when the door is elevated and away from the doorway when the door is lowered, and serving to compel the movement of the door, when elevated, toward the doorway, all without the aid of auxiliary devices, bearing devices affording two points of support for the lower part of the door at different levels and at different distances from the door-opening, the inner point of support being at the higher level and affording an unobstructed path of travel for the door transverse to the frame to its lower outer point of support, and means for guiding the door in its longitudinal travel after it has been moved downwardly and outwardly, substantially as described.

8. The combination with a door-frame, of a vertically-movable sliding door, a groove being provided at the upper portion of the doorway and being higher nearer the doorway and lower away from the doorway, the outer wall or portion *d* of the said groove extending below the top of the door in its lower position, said groove being thus adapted to engage and secure the top of the door close to the doorway when the door is elevated and away from the doorway when the door is lowered, and serving to compel the movement of the door, when elevated, toward the doorway, all with-

out the aid of auxiliary devices, the outer and lower portion of said groove being extended longitudinally of the doorway beyond the same to retain the top portion of the door in its lower outermost position in its horizontal travel, bearing devices affording two points of support for the lower part of the door at different levels and at different distances from the door-opening, the inner point of support being at the higher level and affording an unobstructed path of travel for the door transverse to the frame to its lower outer point of support, and means for guiding the door in its longitudinal travel after it has been moved downwardly and outwardly, and a rail upon which the door is adapted to travel and with which the supporting devices are adapted for engagement, substantially as described.

9. The combination with a door-frame, of a vertically-movable sliding door, a groove being provided at the upper portion of the doorway and being higher nearer the doorway and lower away from the doorway, the outer wall or portion *d* of the said groove extending below the top of the door in its lower position, said groove being thus adapted to engage and secure the top of the door close to the doorway when the door is elevated and away from the doorway when the door is lowered, and serving to compel the movement of the door, when elevated, toward the doorway, all without the aid of auxiliary devices, the outer and lower portion of said groove being extended longitudinally of the doorway beyond the same to retain the top portion of the door in its lower outermost position in its horizontal travel, bearing devices affording two points of support for the lower part of the door at different levels and at different distances from the door-opening, the inner point of support being at the higher level and affording an unobstructed path of travel for the door transverse to the frame to its lower outer point of support, and means for guiding the door in its longitudinal travel after it has been moved downwardly and outwardly, and a rail upon which the door is adapted to travel, substantially as described.

10. The combination with a door-frame, of a vertically-movable sliding door, a groove being provided at the upper portion of the doorway and being higher nearer the doorway and lower away from the doorway, the outer wall or portion *d* of the said groove extending below the top of the door in its lower position, said groove being thus adapted to engage and secure the top of the door close to the doorway when the door is elevated and away from the doorway when the door is lowered, and serving to compel the movement of the door, when elevated, toward the doorway, all without the aid of auxiliary devices, the outer and lower portion of said groove being extended longitudinally of the doorway beyond the same to retain the top portion of the door in its lower outermost position in its horizontal travel, bearing devices upon the lower part of the door affording two points of sup-

port for the lower part of the door at different levels and at different distances from the door-opening, the inner point of support being at the higher level and affording an unobstructed path of travel for the door transverse to the frame to its lower outer point of support, means for guiding the door in its longitudinal travel after it has been moved downwardly and outwardly, and a rail upon which the door is adapted to travel and with which the supporting devices are adapted for engagement, substantially as described.

11. The combination with a door-frame, of a vertically-movable sliding door, a groove being provided at the upper portion of the doorway and being higher nearer the doorway and lower away from the doorway, the outer wall or portion *d* of the said groove extending below the top of the door in its lower position, said groove being thus adapted to engage and secure the top of the door close to the doorway when the door is elevated and away from the doorway when the door is lowered, and serving to compel the movement of the door, when elevated, toward the doorway, all without the aid of auxiliary devices, the outer and lower portion of said groove being extended longitudinally of the doorway beyond the same to retain the top portion of the door in its lower outermost position in its horizontal travel, fixed bearing devices upon the lower part of the door affording two points of support for the lower part of the door at different levels and at different distances from the door-opening, the inner point of support being at the higher level and affording an unobstructed path of travel for the door transverse to the frame to its lower outer point of support, means for guiding the door in its longitudinal travel after it has been moved downwardly and outwardly, and a rail upon which the door is adapted to travel and with which the supporting devices are adapted for engagement, an inclined surface being interposed between said points of support, substantially as described.

12. The combination with a door-frame, of a vertically-movable sliding door, a groove being provided at the upper portion of the doorway and being higher nearer the doorway and lower away from the doorway, the outer wall or portion *d* of the said groove extending below the top of the door in its lower position, said groove being thus adapted to engage and secure the top of the door close to the doorway when the door is elevated and away from the doorway when the door is lowered, and serving to compel the movement of the door, when elevated, toward the doorway, all without the aid of auxiliary devices, the outer and lower portion of said groove being extended longitudinally of the doorway beyond the same to retain the top portion of the door in its lower outermost position in its horizontal travel, means for supporting the door in its elevated or lower position, said means per-

mitting of the free inward-and-upward and outward-and-downward movement of the lower portion of the door, and means for guiding the door in its horizontal travel when lowered, substantially as described.

13. In a door, the combination with a door-frame, of a vertically-movable door, fixed bearing devices upon the door, the inner device being located nearer the car and above the other, whereby when the door is elevated it may be maintained close to the car-body and when lowered it may be supported away from the car-body, said fixed bearing devices affording a free path for the travel of the lower

part of the door in a direction transverse to the car-body and to the side of the car from its inner and upper position to its lower and outer position, and means for guiding the door in its horizontal travel when moved downwardly and outwardly, substantially as described.

In witness whereof I hereunto subscribe my name this 20th day of June, A. D. 1898.

JACOB N. BARR.
